(57) **CLAIM**

The ornamental design for a vehicle front lower grille, as shown and described.

DESCRIPTION

FIG. 1 is a front elevational view of a vehicle front lower grille showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front, and left side perspective view thereof;

FIG. 8 is a bottom, front, and left side perspective view thereof; and,

FIG. 9 is a top, rear and left side perspective view thereof. The portion of the grille shown throughout the drawing views in de-emphasized and half-tone portions inside the broken lines and the broken lines representing the boundary and configuration of what is claimed as the design are for environmental and illustrative purposes only and form no part of the claimed design.

1 Claim, 9 Drawing Sheets
